DESIGN FOR A COCKTAIL SHAKER

Andrew Cravaritis, Roslyn, N. Y.

Application January 22, 1947, Serial No. 136,288

Term of patent 7 years

(Cl. D2—3)

To all whom it may concern:

Be it known that I, Andrew Cravaritis, a citizen of the United States, residing at Roslyn, in the county of Nassau and State of New York, have invented a new, original, and ornamental Design for a Cocktail Shaker, of which the following is a specification, reference being had to the accompanying drawing, forming part thereof.

Fig. 1 is a perspective view of a cocktail shaker embodying my new design;

Fig. 2 is a vertical central sectional view thereof on a slightly enlarged scale;

Fig. 3 is a top plan view; and

Fig. 4 is a bottom plan view thereof.

I claim:

The ornamental design for a cocktail shaker, substantially as shown.

ANDREW CRAVARITIS.
